UNITED STATES PATENT OFFICE.

LUTHER K. JEWETT, OF BOSTON, MASSACHUSETTS, ASSIGNOR TO THE JEWETT SUPPLY COMPANY, OF PORTLAND, MAINE.

SIDE BEARING FOR CAR-BODIES.

SPECIFICATION forming part of Letters Patent No. 427,692, dated May 13, 1890.

Application filed September 6, 1889. Serial No. 323,145. (No model.)

To all whom it may concern:

Be it known that I, LUTHER K. JEWETT, of Boston, county of Suffolk, State of Massachusetts, have invented an Improvement in Side 5 Bearings for Car-Bodies, of which the following description, in connection with the accompanying drawings, is a specification, like letters on the drawings representing like parts.

This invention relates to anti-friction supports or side bearings for car-bodies, and is an improvement upon the anti-friction support shown and described in another application, Serial No. 316,027, filed by me June 29, 1889.

15 My present invention has for its object to improve the construction of the anti-friction supports, as will be described, whereby the side oscillation of the car-body may be compensated for without inflicting strain upon 20 the supporting-springs for the anti-friction device.

Another feature of my invention consists in providing means, as will be described, by which the end-thrust is relieved from the said 25 springs.

My invention therefore consists, essentially, in the combination, with a car-body and its truck, of one or more side sustaining-springs independent of the car-truck and interposed 30 between the said truck and car-body, a firm support for said springs, and a cap or seat for said springs, provided with a semicircular groove, and a cylindrical body fitted into said groove to permit the said cap to rock without 35 lateral motion, substantially as will be described.

Other features of my invention will be pointed out in the claims at the end of this specification.

40 Figure 1 is a side elevation of a sufficient portion of a car-body and its car-truck, provided with my improved anti-friction support or side bearing to enable my invention to be understood; Fig. 2, a transverse section of the 45 car-truck on line $x-x'$, Fig. 1, looking toward the left; Fig. 3, a sectional detail to be referred to, the section being taken on line $x'-x'$, Fig. 1; Figs. 4 and 5, details to be referred to, and Fig. 6 a modification to be referred to.

50 The car-truck A, which may be of any usual

or well-known construction, the chair a, secured, as by bolts a', to the side frames a² of the car-truck and provided, as shown, with the toe a³, adapted to shoulder on the equalizer-bar a⁴, may be substantially such as shown 55 and described in the application referred to.

The chair a has secured to or forming part of it a base-plate b, (see Fig. 3,) provided with a preferably semicircular groove or depression b', into which is fitted or rests a cylindrical or circular body, preferably a rod or bar b², upon the upper half of which is fitted a semicircular groove or depression on the under side of a spring seat, casting, or frame b³, provided, as herein shown, with annular 65 collars b⁴ b⁵, (see Fig. 4,) forming the seats for preferably graduating spiral springs b⁶. The springs b⁶ at their upper ends support a top plate or spring-cap b⁷, provided, as shown, with annular collars b⁸ b⁹, into which the upper 70 ends of the said springs project, the said top plate or spring-cap being provided on its upper side with a preferably semicircular groove or depression, into which is fitted a cylindrical or circular body, preferably a bar or roller b⁹, 75 having fitted upon it the base-plate b¹⁰ of my improved anti-friction device, which is substantially the same as shown and described in the application referred to, it consisting of rollers c, provided with arbors c', upon which 80 are supported a spacing-frame c², the arbor of the center roller c being provided with a pinion c³ in mesh with teeth c⁴ on the base-plate and with like teeth c⁵ on the top plate c⁶, secured to the car-body. 85

The base-plate b is firmly secured to or forms part of the chair a, and as the car-body A' oscillates or sways sidewise the graduating-springs b⁶ are relieved from side strain by the rocking or pivotal movement of the 90 spring-seat b³ on the roller b⁹ and the base-plate b¹⁰ on the roller b⁹.

To relieve the springs b⁶ from strain caused by the forward or backward movement of the car-body with relation to the car-truck, 95 or vice versa, the base-plate b³ is herein shown as provided with uprights or posts d, (see Fig. 4,) having a projecting web d', over which is fitted the legs or arms d² of posts d³, secured to the top plate b⁷, the posts d³ being 100

fitted within and locked by the uprights d d' , so that when either the car-body or the truck is moved endwise with relation one to the other the spring-seat b^3 and the top plate b^7 practically form one casting or piece and transmit the end-thrust to the friction-rollers c , thus relieving the graduating-springs b^6 from strain.

I have herein shown and described the base-plate b as secured to or forming part of the chair; but in some kinds of trucks—as, for instance, in the well-known Wagner six-wheel truck—the base-plate b may be secured to or form part of the housing c (see Fig. 6) for the center wheels of the truck, and in this case the housing c forms a firm support for the anti-friction device.

I have herein shown spiral springs; but instead thereof elliptical springs may be used.

I have specifically described the side bearing-springs as used to support the anti-friction device, and while in most cases the two parts will be used together, I do not desire to limit my present invention in this respect, as the rocking cap and seat may be used to advantage when the springs rest on a firm support, such as described, and the base-plate b^{10} is secured to or forms part of the car-body. I prefer to rock both the cap and seat for the said springs, as by this means all the strain caused by the side oscillation of the car is relieved from the said springs; but, if desired, only one part, as the cap, may be made to rock, and the other part, as the seat, may be made stationary. In this case the upper part of the springs would be relieved from strain.

I am aware that a car-truck has been constructed in which the springs supporting the

bolster have been provided with a cap having a shallow groove in which rests a cylindrical body secured to the bolster. In this construction the cap is free to oscillate or slide laterally on the said cylindrical body. This construction is impracticable for my purpose.

I claim—

1. The combination, with a car-body and its truck, of one or more side sustaining-springs independent of the car-truck and interposed between the said truck and car-body, a firm support for said springs, and a rocking cap or seat for said springs, provided with a semicircular groove, and a roller fitted into said groove to permit the said cap to rock without lateral motion, substantially as described. 45

2. The combination, with a car-body and its truck, of an anti-friction device, substantially as described, a firm support for said anti-friction device, one or more springs to support said anti-friction device, and a rocking cap or seat for said springs, substantially as described. 50

3. The combination, with a car-body and its truck, of one or more side sustaining-springs, a firm support for said springs, and a rocking cap or seat, and means to lock said spring-cap within the spring-seat, whereby the said springs are relieved from strain by end-thrusts, substantially as described. 55

In testimony whereof I have signed my name to this specification in the presence of two subscribing witnesses.

LUTHER K. JEWETT.
